(57) **CLAIM**

The ornamental design for a digital photo frame, as shown and described.

DESCRIPTION

FIG. 1 is a front perspective view of a digital photo frame, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and

FIG. 9 is a partial enlargement view of the encircled portion marked "9" of FIG. 1.

The broken lines in the drawings illustrate the portions of the Photo Frame, which form no part of the claimed design.

The dot-dash broken lines encircling a portion of the digital photo Frame in FIG. 1 and illustrated in FIG. 9, depict the boundaries of the enlarged view and form no part of the claimed design.
